GOLF SWING TRAINER

Dale F. Pinkerton, Alexandria, Va., assignor to
Aleane Cloward Pinkerton, Alexandria, Va.

Application September 30, 1949, Serial No. 118,896

5 Claims. (Cl. 273—35)

1

The present invention relates to improvements in golf swing trainer and has for an object to provide a means for the application of weight to a golf club without disturbing its balance in order that the user of the club may in practice be obliged to overcome the greater inertia of the superadded weight which will tend to slow his swinging stroke and to otherwise inculcate in him correct swinging movements of the club.

Golfers are prone to hit from the top of the back-swing without first unwinding the body and the shoulders in an initial movement and golfers in their hurry to hit the ball will uncock the wrists either at the top of the back-swing or at an early stage of its movement. All of which are faults contributing to lack of distance, slicing and hooking and certainly these faults prevent the proper speeding of the golf club head when it reaches that part of the arc of its movement at which the ball is addressed. The added weight of the new device will subconsciously impress on the trainee that these faults are being committed and will assist rectifying the same so as to smooth the golf swing and enable it to be carried out in a manner prescribed for the best results.

The invention also contemplates the use of a training device of simple form readily applicable to and removable from the club and which will in no way interfere with the striking surface of the club so that practice balls may actually be hit with the device in place on the club.

A still further object of the invention is incident to the position of the weight mass on the golf club where it occupies a situation with its weight symmetrically distributed with respect to the axis of the golf shaft along which the centrifugal force is developed incident to the golf swing.

With the foregoing and other objects in view, the invention will be more fully described hereinafter, and will be more particularly pointed out in the claims appended hereto.

In the drawings, wherein the symbols refer to like or corresponding parts throughout the several views,

Figure 1 is a fragmentary perspective view of a golf shaft and club head showing applied thereto a golf swing training device constructed in accordance with the present invention.

Figure 2 is an end elevational view of the same showing the position of application of the device and its split end.

Figure 3 is a perspective view, taken on an enlarged scale, of the training device apart from the golf club.

Figure 4 is a vertical section taken on the line 4—4 of Figure 3.

Figure 5 is a transverse section taken on the line 5—5 in Figure 1.

2

Figure 6 is a view similar to Figure 2 showing a modified form of the training device, and

Figure 7 is a transverse section taken on the line 7—7 in Figure 6.

Referring more particularly to the drawings, 10 designates a shaft, 11 the head and 12 the whipping about the shank between the shaft and head, all as in accordance with conventional construction.

In one of its forms the improved training device is or may be constituted of a block of rubber or other resilient material having an outer wall 13 of any desired configuration, for instance a frusto-conical end with flat or other shaped top and bottom walls 14 and 15 respectively.

Preferably coincident with the axis of the cone is a frusto-conical bore or opening 16 extending to and through both lower and upper bases 15 and 14 of the conic frustum. The lower portion 20 of the bore 16 may be made downwardly flaring if desired. A radial or other slot 17 is made in the rubber block opening through the outer wall or lateral surface 13 of the cone and also opening through both lower and upper bases 15 and 14. At its inner end the slot 17 opens through the bore 16. In other words the mass of the rubber block is incised substantially radially, the width of the incision being of any desired dimension less than the diameter of the shaft 10 and shank 12 of the golf club.

In the use of the device, the rubber block may be distorted by applying substantially tangential forces at opposite sides of the slot 17, such forces being applied manually, for the purpose of opening the slot 17 wide enough to slip the block over the shaft 10; following which procedure the block or mass is moved down on to the shank 12 with its bore 16 including the lower flaring portion thereof frictionally or resiliently gripping the shank portion, the external whipping providing and excellent grip for this purpose. The diameter of the bore 16 at one portion at least is preferably slightly less than the external diameter of the included portion of the shank 12 whereby the slot 17 will be maintained abnormally open to a greater degree than that to which the stress inherent in the rubber body biases such slot 17; this being for the purpose of taking advantage of the resilient stress inherent in the resilient body 25 to at all times maintain firm gripping engagement with the shank 12 and its external whipping. This avoids looseness between the training device and the golf club which would be undesirable and would give potential rise to relative movements between these parts incident to the swinging of the golf club which attains a high acceleration particularly in and about the club head thus developing a rather high centrifugal force which in the present construction is taken 30 advantage of by the position of the mass on the

shank and the construction of such mass with its flaring and frusto-conical bore and by reason of the resilient material out of which this block is made; inasmuch as the centrifugal force will tend to move the mass outwardly on the shank thus tending to open the slot 17 wider and place the mass under progressively greater resilient stress which therefore hugs the shank tighter in proportion to the centrifugal force developing in the mass.

The block or mass will possess a weight, for instance of the order of two ounces, which is in addition to the particular weight of the golf club employed and consequently while generally the "feel" of any particular golf club to which the device is applied will not be greatly, if at all, altered by the application of the device, nevertheless additional weight is added to the golf club which will have a number of desirable attributes particularly as a training implement. For instance the weight will naturally slow the swinging movement of the golfer to avoid hurrying his stroke which is a fault in the orthodox golf swing. Again a few practice swings with the improved device applied just before teeing off will make the club feel much lighter in the hands of the golfer after the device has been removed and when the golfer addresses his ball for the drive, this advantage being akin to that derived by baseball players in making preparatory swings with two bats.

After such practice or preparatory swings have been executed, the player may easily detach the device from the club and for this purpose the lower base 15 at the tapering shank of the club head 11 affords a large striking surface for the hand or for any implement in dislodging the block upwardly along the reduced section of the shank 12 whereby the block may be quickly slid to such reduced section or to the smaller diameter of the shaft 10 whereupon the device may be pulled radially from such shaft through the slot 17 or the slot may be consciously and forcibly opened to permit the separation of the mass from the club.

It will be apparent that the device will not mar the head 11 of the club. It is also located out of the way of the striking face 18 of the club head so that it does not interfere with hitting a practice ball. The device is small and can be conveniently carried in the ball pocket of a golf bag. It will fit any club regardless of size or shape of head. The device may be made entirely of rubber or synthetic rubber or any resilient material or compositions of the same.

The device is economical of manufacture and is simply applied and removed.

Referring more particularly to Figures 6 and 7, a modification is herein shown in which the mass is globular rather than frusto-conical. The spherical ball is indicated at 13^a and the slot at 17^a. In this instance the segments at opposite sides of the slot 17^a may be held together to prevent the slot 17^a from abnormally gaping. A simple form of device for this purpose is the strap 19 which may be made of a different or softer rubber than the mass of the training device and incorporated therewith permanently at one side of the slot 17^a as by vulcanization or by the use of cement. This strap 19 is long enough to bridge the slot 17^a and to overlap a fastening member 20 which may be embedded in the mass of the rubber device and have an end projecting radially from the sphere in position to have snapped over it the eyelet 21 carried by the free

end of the strap 19, which eyelet complements the fixed fastener 20 and forms an interlocking couple therewith. The eye and the free end of the strap 19 may be separated from the fastener 20 by simply pulling the free end of the strap radially outward. The strap 19 may stretch within desirable limits.

While it is greatly preferred that rubber or some resilient material be employed as the material for the training device, it is possible that a similar device may be made from wood, metal or some other non-resilient material in which event some such device as the fastening strap 19 would be employed to hold a hinged section of the device in place, such section being swingable outwardly to apply and remove the device to and from the golf club.

Although I have disclosed herein the best form of the invention known to me at this time, I reserve the right to all such modifications and changes as may come within the scope of the following claims.

What I claim is:

1. A golf swing training device for use with a golf club having a head, shaft and shank connecting shaft to head comprising a resilient weighted mass having opposing ends and having a bore therethrough and through the ends, said bore formed to resiliently grip said shank of a golf club above the head, and said mass having a radial slot extending from end to end to communicate said bore with the outside edge of the mass so that the mass can be passed transversely onto the shank, said mass having one end directly above the head when situated on the shank.

2. A golf swing training device as claimed in claim 1 characterized by the fact that a resilient strap bridges said slot and is secured on either side of said slot to prevent abnormal opening of said slot.

3. A training device for golf clubs comprising a resilient block having opposing ends and having a bore extending through the block and through the ends and adapted to be wedged downwardly upon the shank of the golf club, said block having a single slot parallel to the bore extending from end to end and communicating with said bore to admit application to and removal from the shank of a club.

4. A training device as claimed in claim 3 characterized by the fact that the bore is substantially tapering to closely fit the shank and its whipping.

5. A training device as claimed in claim 3 characterized by the fact that a locking means bridges said slot and is secured on opposite sides of said slot to prevent abnormal opening of said slot.

DALE F. PINKERTON.
